UNITED STATES PATENT OFFICE.

ALFRED EDWIN DAVIS, OF JOHANNESBURG, TRANSVAAL, ASSIGNOR OF THREE-FIFTHS TO RICHARD MEYER, OF JOHANNESBURG, TRANSVAAL, FRANCIS HASTINGS MEDHURST, OF WESTMINSTER CHAMBERS, LONDON, ENGLAND, AND JOHN EDGAR FERRAR, OF JOHANNESBURG, TRANSVAAL.

TRANSPORTING APPARATUS FOR MINES.

No. 918,661.

Specification of Letters Patent.

Patented April 20, 1909.

Application filed September 30, 1907. Serial No. 395,198.

To all whom it may concern:

Be it known that I, ALFRED EDWIN DAVIS, a subject of the King of Great Britain, and resident of Johannesburg, Transvaal, have 5 invented certain new and useful Improvements in Transporting Apparatus for Mines, of which the following is a specification.

This invention consists of improvements in and relating to transporting apparatus for 10 mines.

The object of the invention is to provide efficient means for transporting broken ore or mineral in mines, both in the stopes, levels and crosscuts, rises and winzes, or from 15 any portion of a mine where the rock or mineral is being mined to any other portion of a mine.

The invention consists in certain features in the construction of the trucks, cars or vehicles, and the rails traversed by such vehicles, as hereinafter fully described. The rails are 20 of such construction that they can be moved expeditiously from time to time so as to keep the rail or track at an approximately uniform 25 distance from the broken coal, rock or mineral, or the working face, and so allow the vehicles to be run parallel to such face loaded direct in the stope, and thence allowed to gravitate down the stope to the drive and if 30 desired, to the shaft.

It is requisite in a transporting apparatus of the nature specified that the trucks, empty or full, shall be able to run freely in either stopes, drives or shaft, or on the surface; that 35 they shall be capable of running freely in the narrowest of stopes and of being loaded in such stopes; that when loaded they shall be capable of ascending and descending the steepest of gradients without spilling the 40 contents; that they shall be capable of negotiating sharp points, bends or curves in the rails, both horizontal and vertical; that they shall be incapable of capsizing or derailing in both stopes and drives; that they shall be 45 capable of carrying loads of half a ton or more; and that they shall be of such a shape as to allow the trucks or vehicles to pass one another freely in drives of ordinary dimensions and thereby to obviate delays in trammimg or transportation of the rock or mineral in long levels. Suitable means must also be provided for easily and quickly discharging 50

the loaded trucks. It is further requisite that the rails constituting the track traversed by the vehicles shall be light, strong, easily 55 handled, capable of being moved easily and expeditiously from place to place; that there shall be freedom from loose parts which might be lost or mislaid; that they shall be stiff vertically so as to carry the necessary 60 load with as few sleepers as possible; that they shall be flexible at the supporting joints; that they shall always be maintained truly 65 vertical and also allow one length of rail to swing up and down and sidewise relative to the next one so as to follow the inequalities or undulations of an uneven floor and that if necessary they shall be capable of being bent to any sharp curves without permanent set.

To facilitate the detailed description of 70 my invention I append drawings illustrative thereof, in which—

Figure 1 is a side elevation partly in section of one of the trucks, cars or vehicles, on the rail. Fig. 2 is a transverse section of 75 Fig. 1 on line $x-x$. Fig. 3 is a plan of Fig. 1 with one of the dish shaped bearing pieces removed and showing the wheeled bogie in plan. Fig. 4 is a side elevation of the wheeled bogie with the dish shaped bearing 80 piece in section. Fig. 5 is a section of Fig. 4 on line $y-y$. Fig. 6 is a plan of Fig. 4 looking from below. Fig. 7 is a side elevation of the wheeled bogie in position on the rail, illustrating the provision of a guide strip on 85 the saddle of the bogie. Fig. 8 is an end elevation of Fig. 7 with one of the wheels of the bogie removed. Fig. 9 is an end view of the truck in the tippler. Fig. 10 is an end view of the truck on a pivoted or swinging rail, 90 being an alternative arrangement to Fig. 9. Fig. 11 is a plan of one end of the truck illustrating it equipped with buffer and drawbar. Fig. 12 is a plan of a portion of the truck showing a modification in the arrangement 95 of the buffer and drawbar. Fig. 13 is an end elevation of Fig. 12. Fig. 14 is a side elevation of the rail and one form of joint, showing part of the side plate of the rail removed. Fig. 15 is a section of Fig. 14 on line $x'-x'$. 100 Fig. 16 is a section of Fig. 14 on line $y'-y'$. Fig. 17 is a longitudinal elevation of the sleeper illustrating a means of supporting the rail and fixing it vertically thereon, the rail

being shown in section. Fig. 18 is an end elevation of Fig. 17 with the rail removed. Fig. 19 is a side elevation illustrating a hinge joint between two lengths of the rail and 5 showing part of the side plate removed and the sleeper in position. Fig. 20 is a section of Fig. 19 on line $z-z$. Fig. 21 is an end elevation of the sleeper showing a means of adjusting the horns which carry the rail. Fig. 10 22 is a side elevation of Fig. 21. Fig. 23 is an elevation, partly in section, illustrating means for bolting two consecutive lengths of rail to the horn on the sleeper. Fig. 24 is an end elevation of Fig. 23. Fig. 25 is a view 15 similar to Fig. 23 illustrating a modification. Fig. 26 is an end elevation of Fig. 25. Fig. 27 is a view similar to Fig. 25 illustrating a further modification. Fig. 28 is an end elevation of Fig. 27. Fig. 29 is a plan of a 20 curved fish plate. Fig. 30 is an elevation of Fig. 29. Fig. 31 is a longitudinal elevation of a sleeper illustrating means for adjusting the position of the horn carrying the rail, in relation to the sleeper, also illustrating an 25 end elevation of a slightly modified form of truck, the latter with the wheels and bogie removed. Fig. 32 is a plan of the sleeper and adjustable horn illustrated in Fig. 31. Fig. 33 is an end elevation of Fig. 32. Fig. 34 is a 30 longitudinal elevation of the truck illustrated in Fig. 31. Fig. 35 is a plan of Fig. 34. Fig. 36 is a side elevation of a portion of the truck illustrated in connection with Fig. 31, showing means for automatically releasing the 35 hinged sides to discharge the truck. Fig. 37 is a transverse section of a portion of Fig. 36. Fig. 38 is an end elevation of a portion of the truck illustrated in Fig. 36. Fig. 39 is a side elevation of the rail illustrating a switch and 40 other details. Fig. 40 is a plan of Fig. 39, and Fig. 41 is a diagrammatic representation of a stope and drive or lever, showing the invention installed in the stope.

In Figs. 1, 2 and 3, I illustrate one form of 45 the truck, car or vehicle, and show it in running position on the rail. The truck comprises a long narrow and shallow trough shaped body 1, which may be of steel or other suitable metal, the ends of which are closed 50 by means of the end plates 2, riveted or otherwise suitably fixed to the body. Intermediate of the end plates 2 the body 1 is fitted with a suitable number of transverse plates 3 (it is shown provided with three) riveted or 55 otherwise fixed to the body and dividing it into a plurality of compartments. These transverse partitions or division plates 3 serve to prevent the spilling of the ore or mineral by preventing it sliding or moving 60 down the body when the latter is inclined at steep angles; they also act as stiffening pieces for the body.

It will be apparent that the body 1 of the truck instead of being made of semi-circular 65 transverse section as shown in Figs. 1 to 3

and 11 to 13, may be made of rectangular cross section, or it may be constructed of substantially W transverse section as illustrated in Figs. 31, 34 and 35, or of any other desired and suitable shape.

The body 1 is mounted upon two swivel or bogie carriages which latter are shown drawn to an enlarged scale in Figs. 4 to 6. These bogie carriages run on the rail or track 4, the features in the construction of which 70 are hereinafter particularly described. The bogie carriages are revolvably connected to the body 1 through the medium of dish shaped bearing pieces 5, which latter are shown constructed with flanges for riveting them in position to the body 1. The revolvable connection between the dish shaped bearing pieces 5 and the bogie carriage is made by an eyebolt and nut 6 passing through a hole in the bearing piece 5, and a pivot plate 7, 80 which latter is located immediately beneath the bearing piece 5 and is formed with a hole through which said eyebolt 6 projects.

8 is a pivot pin passing through holes provided in projections 9 formed on the underside of the pivot plate 7, and passing through the eyebolt 6 and engaging holes formed in the upper portion of the bogie carriage. The latter comprises the main frame or saddle casting consisting of the two side plates 10 connected by the transverse rib 11. The side plates 10 carry the two axles 12 upon which are mounted the flanged wheels 13 which are adapted to traverse the rail 4. The frame is also constructed to provide the 100 two downwardly projecting arms 14 which carry the vertical axles 15 (see Fig. 5) on the lower extremities of which are mounted guide wheels 16. These latter wheels 16 engage the sides of the rail in its lower portion, 105 and serve to maintain the truck in equilibrium, as is clearly illustrated in Figs. 1 and 2.

The construction of bogie carriage as above described enables it to rotate in a horizontal plane around the eyebolt 6 and also to swing or tilt in a vertical plane by means of the pivot plate 7 and the pivot pin 8. The resulting effect of the latter motion is that as the vehicle is passing over the rail joint at a 110 change of gradient, the leading wheel 13 can obtain a bearing on the forward rail before the following wheel leaves the rear rail.

In Figs. 7 and 8 I show the bogie carriage provided with means for preventing the wheels 13 rising above the rail and rotating about the pivot bolt 6 to such a position as to place the wheels 13 transversely of the rail 4. These comprise the guiding strips 17 turned outward at their extremities, which strips in the normal running of the truck run clear of the sides of the rail 4, see Fig. 8. In the event of any tendency of the wheels 13 and bogie carriage to twist too far about the pivot bolt 6, then the strips 17 will come into contact with or engage the sides of the rail 4, 120 125 130

and sliding along it so prevent the further twisting of the carriage and wheels 13 and as a consequence maintain them in correct running position on the rail. Should the wheels 13 tend to ride up on the rail 4 on their flanges, the strips 17 contact with the sides of the rail and so prevent the flanges rising to the top of the rail. The effect is to cause the wheels 13 to slip back into position again on the top of the rail and not to leave the track. The strips 17 are shown fixed by rivets or bolts 18 in a slot or groove 19 formed in the inside of the side plates 10, or in downward extensions 20 of the transverse rib 11 connecting the side plates. The strips 17 may be renewed from time to time as required. It will also be understood that the downward extensions 20 carrying the guide strips 17 also operate to prevent the wheels 13 riding up on to the rail.

The trucks are preferably equipped with a brake or brakes which may be conveniently attached to one of the bogie carriages as shown in Figs. 4 and 6. In the particular construction of brake illustrated 21 are two links or arms fixed on the axle 12 of one of the wheels 13. These links or arms 21 carry a spindle 22 and mounted on the spindle between the links is a pair of brake blocks 23, 24 which are shaped to fit the head or top of the rail 4. For the purpose of drawing the brake blocks 23, 24 together to grip the rail 4, the spindle 22 passes loosely through a hole in the block 23 and is screwed through the other block 24, so that when the spindle 22 is rotated the blocks are drawn together. The spindle 22 is provided with a handle 25 at one extremity and at the other carries a spring washer 26 or its equivalent placed between the head of the spindle 22 and the arm 21 in order to keep a steady pressure on the rail 4 when the truck is moving down an incline, so as to insure the lowering of the loaded vehicle at a substantially uniform safe rate of speed. It will be apparent that any other convenient form of brake may be employed arranged either to act upon the wheels 13 or the rail 4, in any ordinary manner, as may be preferred.

In Fig. 11 the truck or vehicle is shown equipped with a buffer 26 and a bridle or drawbar 27 for hauling. The buffer 26 is a suitably shaped piece or block of wood fitted to the end of the body 1 of the truck and bedded against the end plate 2. It is held in position on the end of the truck and protected by a strip or band 28, which may be either a continuation of the body 1 as shown, or of the end plate 2, or a separate piece riveted or otherwise suitably fastened either to the body or end plate. The bridle 27 which serves for making the connection between the hauling rope and truck, may consist of the metal bar shaped as shown and riveted at its extremities to the ends of the

sides of the body, said ends being bent inward as shown to provide a double thickness of the metal to which the bridle is fixed.

In the modification illustrated in Figs. 12 and 13, which is applicable more particularly for a truck designed for a train of vehicles or heavier loads, the bridle 27 is shown in the form of an endless bar running completely around the truck and secured along the longitudinal edges by bending them completely around the bar. At the ends a block 29 of wood or other suitable material is arranged between the end plate 2 and the end of the bridle 27 so as to transmit part of the thrust on to the end plate. 30 represents a space formed between the block 29 and the end of the yoke 27 for making the connection with the hauling rope. The buffer block 26 may be fixed next the end plate 2 in the manner described in connection with Fig. 11 and the two blocks 26, 29 be bolted or otherwise connected. If preferred the end strips or bands 28 may be made sufficiently strong to serve as the buffers without the wooden blocks 26, in any case however it is necessary that said strips or bands 28 or the buffers 26 shall project sufficiently far forward to prevent damage to the bridles 27. Obviously other means may be provided for making the connection between the vehicle and the hauling rope.

In Fig. 9 I illustrate one arrangement for discharging the trucks of the construction previously described. This arrangement or tippler is also shown in conjunction with the general arrangement illustrated in Fig. 41. It comprises a suitable length of rail 4 riveted or otherwise suitably fixed to two rings 31 located at or in proximity to the ends of the rail 4. The rings 31 are revolvably supported upon rollers 32. To increase the rigidity of the tippler, the rings 31, as shown in Fig. 41, are connected by a suitable number of bars 33. To the vertical sides of the rail 4 are riveted or otherwise suitably fixed check strips 34. 110 These strips 34, as will be seen on reference to Fig. 9, engage the flanges of the guide wheels 16 when the truck is inverted and so prevent the latter leaving the rail. 35, in Fig. 9, represents an ordinary jockey or rope grip in place of the bridle 27, for making the connection between the truck and the hauling rope.

In Fig. 10 I illustrate a modified arrangement for discharging the trucks. In this construction the length of the rail 4 on to which the truck is run to be inverted is supported at or in proximity to its extremities by pivots or hinged joints 36. The rail is provided with the check strips 34 for engaging the guiding wheels 16, and a balance weight 37 is fixed to the rail 4 so that after the loaded truck has been discharged it returns the empty truck and rail to the vertical position.

In certain circumstances, as for example 130

in stopes where the trucks are used only for transporting the broken ore down from the working face and discharging it into the stope boxes, it may be found more convenient to dispense with the automatic discharging arrangements just described and to construct the truck on the principle of a self-discharging truck as illustrated in Figs. 31, 34 and 35. In the construction shown in these figures, 38 is an inverted V or substantially V shaped girder which constitutes the bottom and is carried upon two of the bogie carriages—see Figs. 4 to 6. The partitions or division plates 3 and end plates 2 are bolted or riveted to the girder 38 and so act as stiffeners for the body. The sides 39, which as shown in Fig. 31, are adapted to swing outward, are hinged along their upper edges on a rod 40 carried by perforated lugs or projections 41 provided on the upper edges of the partitions 3 and end plates 2. The upper edges of the sides 39 are bent around the rods 40 between the aforesaid projections 41 and are riveted at 42—see Fig. 31. The bottom of the truck being inclined from the center to the sides, when the sides 39 are opened the contents of the truck are discharged.

The dish shaped bearing pieces 5 connecting the bogie carriages with the body are fashioned with suitable flanges, as in Figs. 4 to 6, for riveting them to the girder.

In Figs. 36, 37 and 38, I illustrate means designed for maintaining the hinged sides 39 in their closed position and for automatically releasing the sides to discharge the contents of the truck at any predetermined point. In this construction brackets or clips 43 are riveted at or in proximity to the bottom edges of the sides 39. These clips 43 support a bar 44 which is adapted to be moved longitudinally of the sides within certain limits in either direction. The sliding bar 44 is constructed with projections 45. To the partitions or division plates 3 and end plates 2 are riveted pieces 46 which when the sides 39 are closed, project through holes formed in the sides. In the ends of the pieces 46 are formed slots with which the projections 45 on the sliding bars 44 engage to lock the sides 39. To each of the sides 39 is pivoted a depending arm or lever 47 and to the sliding bar 44 is fixed a roller 48 which is adapted to be engaged by the arm 47. 49 is a stop which may be fastened to one of the sleepers or otherwise as may be preferred and at any desired point, which stop 49 is adapted to engage the arm or lever 47 to cause the latter to engage the roller 48 and so move the sliding bar 44 longitudinally of the side to cause the projections 45 to disengage the slots in the pieces 46. When this is accomplished the contents of the truck move the sides 39 outward and are thereby discharged.

65 If desired means such as a spring or springs

may be used for maintaining the sides 39 open so as to allow them to run clear of any mineral or ore at the sides of the vehicle, and which might prevent the closing of the sides after discharging.

With the object of minimizing the weight of the truck and reducing the cost of manufacture and also to reduce the labor necessary for removing the rails from place to place, I preferably provide means for supporting each length of rail at or in proximity to each extremity only. It is requisite that such supports or sleepers provide for the fastening of one length of rail to the next in such manner as to prevent mutual longitudinal displacement; to secure each length of rail to the rail support, to keep the rail in a vertical position independently of the angle at which the sleeper rests upon the ground; to provide such joints between successive lengths of rail as to allow each length to be moved up or down in a vertical plane so that the angle of inclination between any two adjacent lengths may be altered in order that the rail may adjust itself to the varying inclination of the floor; and to provide that each length of rail may be capable of being bent in a horizontal plane either to right or left to allow of the rails following any desired curve without permanent set. To meet these different requirements the rails, supports and sleepers are constructed and arranged as will be described.

In Figs. 1 to 3, and drawn to an enlarged scale in Figs. 23 and 24 I illustrate a rail 4 which, being inexpensive to manufacture, is the preferred form of rail. It is manufactured in suitable lengths from sheet steel or other suitable metal of the necessary width. The sheet is bent to form the two vertical sides 50 and the top or tread 51 of the rail. The sides are maintained parallel by the employment of tubular or other suitable distance pieces 52 through which pass the rivets 53. In place of the distance pieces 52 and in order to make a stiffer rail, the sides 50 of the rail may as shown in Figs. 25 and 26, be bent inward at the bottom to form the flanges 54 connected by the rivets 55, or, as shown in Figs. 27 and 28, the one side of the rail may be bent inward at the bottom to form an internal flange 56 and the other side be bent inward at the bottom to form the external or overlapping flange 57 in the form of a lap joint, connected by the rivets 58. It will be apparent that in rolling plates for the manufacture of these rails it will be possible to make that portion which forms the tread 51 thicker (as shown in Fig. 2) than those portions which form the sides and thus provide for the wearing away of the tread. Further, it will be evident that the parts which form the vertical sides of the rails may be rolled with an external projecting ridge at each side, at or in proximity to the bottom, be-

neath which the guiding wheels 16 of the bogie carriages would run and thus prevent derailment of the trucks and also serve the purpose of the check strips 34 on the tippler 5 rail 4, shown in Figs. 9 and 10.

In Figs. 14, 15 and 16, I illustrate a rail which is flexible laterally. The rail consists of the two side plates 50 of steel or other suitable metal with an intermediate filling 10 piece 59 of wood or other suitable material, all riveted together as at 60. The top or tread of the rail may consist of a steel bar 61 resting on the filling piece 59 between the upper ends of the side plates 50, the latter 15 serving to keep it in place laterally. The bar 61 forming the tread is fastened to the wood lining or filling piece 59 by means of counter-sunk headed screws 62 screwed into the wood, or by means of counter-sunk 20 headed eyebolts 63, which latter may, as shown in Fig. 14, be held in position by the rivets 64 which serve for fastening together the side plates 50 and lining 59. If desired to obtain greater flexibility in the rail a steel 25 wire or other suitable rope might be used in place of the bar 61 to form the tread, or the tread might consist of a number of thin vertical strips. In connection with Fig. 17 I illustrate an alternative mode of securing 30 the bar 61 which constitutes the tread of the rail, in which said bar 61 is beveled at the sides and the upper edges of the side plates 50 are beaded or bent inward to retain the bar 61 in position between them.

35 In the construction of the rail illustrated in connection with Fig. 17 and also in Figs. 19 and 20, a strip 64 of steel or other suitable metal is located in a recess at each side of the rail between the side plates 50 and the 40 wood lining 59. Upon these strips 64 the bar or tread 61 is bedded. The strips 64 are supported by the rivets 60 which secure them to the side plates 50 and wood lining 59.

45 As shown in connection with Figs. 14 and 16 joints between consecutive lengths of rail are made by means of fish plates 65 which are arranged on the inside of the side plates 50 of the rail (see Fig. 14) the wood lining 59 50 being cut away or recessed at the joint to receive them, 66 representing bolts passing through the side plates 50, fish plates 65 and wood lining 59 and bolting them together. By this construction the sides 50 of the rail 55 on the outside are maintained parallel or of uniform width, thereby providing a continuous flat surface or rolling path for the guide wheels 16 of the bogie. All rivets and bolts passing through the sides of the rails are arranged above and below the path of the 60 wheels 16 so as to provide a clear unobstructed track therefor.

In Figs. 17 and 18 I illustrate a form of sleeper and support for the rail suitable for 65 use in narrow stopes and for the construc-

tion of rail described in connection with Figs. 14 to 16 and 19 and 20. The sleeper 67 consists of a suitable short length of channel iron to which is riveted or otherwise suitably fixed one or more of the pieces 68, 69, 70, 75 70 which constitute the rail supports or carriers. The sleeper 67 is shown provided with three of such horns or rail carriers riveted on to the top of the sleeper. The horns 68, 69, 70, which may be made of iron or steel are 80 bent to the requisite shape so as to assume the desired angles when fixed to the sleeper. The horns 68, 69, are shown fashioned out of one strip of metal of a thickness approximately equal to half the thickness of the 85 wood filling 59. The other support 70 is shown built up or composed of two pieces riveted together as at 71 by one or more countersunk rivets. It will be apparent that all three horns 68, 69, 70 might be built 90 up similar to the horn 70, or be fashioned out of one piece of material like the horns 68, 69, the parts being suitably riveted together and to the sleeper 67. The object in providing the sleeper 67 with the three horns as 95 shown is to obviate or reduce to a minimum the labor involved in packing up or raising one end or other of the sleeper in order to make the horn or rail carrier truly vertical. This may be explained by taking as an example a stope dipping at an angle of say thirty degrees. In such a stope in order to support the rails vertically while the rail is moved into positions of varying inclination it would be necessary either to pack up the 100 sleeper at one end or to make provision for adjusting the supporting horn for the rail if one only were provided. Assuming that the horn 69 is vertical and the horn 70 fixed at an angle of fifteen degrees from the vertical 105 and the third horn 68 fixed at an angle of thirty degrees from the vertical, this would make a maximum of seven and a half degrees to be compensated for by packing up the sleeper 67. When the sleeper 67 is 110 equipped with a number of the horns they must be so disposed that when any one is being used as the support for the rail 4 the guide wheels 16 on the bogie will clear the other horns.

115 In Fig. 19 the rail is shown arranged in position on the supporting horn 70 of the sleeper 67. At the points where the sleepers are placed a portion of the wood lining 59 is cut away or omitted, as at 72, so as to leave 120 a space for the horn. Arranged as shown the weight of the rail 4 and the vehicles traversing the rail, is carried by the horn 69 through the medium of the strips 64 which rest directly upon it.

125 Instead of supporting the rail through the strips 64 it may be supported by means of a suitable number of bolts 73 passing through the rail and horn as shown in Fig. 19. The holes for one or more of the bolts 73 are pref-

erably provided in any case so that one or more bolts may be inserted to connect the rails and sleepers while they are being moved.

5 In Figs. 1 and 2 the rail 4 is shown supported along its bottom edges which rest upon the top of the sleeper 67, the horn 74 not extending upward sufficiently far to engage the top or tread 51 of the rail, but 10 merely acting to support the rail laterally. In these figures the horn 74 is shown passing through a slot in the top of the sleeper 67 and bent outward beneath it to form flanges 75 for riveting it to the sleeper.

15 In Figs. 21 and 22 I illustrate another means for adjusting the horns or rail carrier 76 to maintain the latter vertical. In this construction a bolt 77 is employed which passes through the flanges of the sleeper 67, 20 which as shown may be inverted, or have brackets fixed to the sides to carry the bolt 77. This bolt 77 forms a pivot about which the lower end of the horn 76 may be moved to vary its inclination to the plane of the 25 sleeper 67. Riveted or otherwise suitably fixed to the flanges or brackets carrying the bolt 77 are two side plates 78 of semi-circular or approximately semi-circular shape. In each of these plates 78 is formed a slot 80 30 radial to the center of the bolt 77. 79 is another bolt which passes through the horn 76 and at its extremities projects through the radial slots 80 in the side plates 78. By loosening the nut screwed on one extremity 35 of the bolt 79 the horn 76 can be moved about the pivot bolt 77 into any desired position in relation to the sleeper 67 to maintain the rail vertical. The tightening of the nut clamps the horn 76 in its adjusted position.

40 In Figs. 31 to 33 I show another means for adjusting the horn 81 in relation to the sleeper 67, which construction obviates the necessity for the use of nuts and spanners.

45 In this construction the lower ends of the horn 81 are turned outward in opposite directions in the form of flanges 82, 83, which constitute the base. The sleeper 67, as in the last preceding construction, may be inverted or be formed with or have fixed to it brackets for carrying two transverse bolts 84, 85. The end of the flange 82 of the rail carrier is curved and projects underneath the bolt 84, around which it may hinge or 50 move. The other flange 83 is constructed with a slot. 86 is a bar which is curved at its lower extremity and fits under the other bolt 85 about which it may move. This bar 86 projects up through the slot in the flange 55 83 and has formed through it a plurality of holes, see Fig. 33. 87 is a pin which is adapted to be passed through any one of the holes in the bar 86 to support the horn or carrier 81 in any desired position. This pin 60 65 87 is preferably connected by means of a

chain or otherwise with the sleeper 67 to prevent it being lost or misplaced.

In connection with Figs. 23 and 24 I show one mode of securing the ends of rails 4 on the rail carrier or horn 88. The ends of the 70 rails 4 rest upon the top of the horn 88 and through the side plates 50 of the rails are formed holes and in the horn 88 are formed holes adapted to be brought into coincidence therewith. 89 are nuts and bolts passing 75 through the holes aforementioned for bolting the rails 4 to the horn 88. With this construction sufficient play is allowed at the joints to permit of the rails being rotated about the bolts 89 in a vertical plane. If 80 the sides 50 of the rail 4 are made of sufficiently thin material it is found in practice that this provides sufficient flexibility in the joint to allow of the rails being placed at a considerable angle to one another in a horizontal plane. In this case the rails can be supported by resting on top of the horn 88, or they may be supported by resting on the top of the bolts 89.

In the modification illustrated in Figs. 25 90 and 26, the contiguous extremities of the rails 4 are connected by latches or pivoted hooks 90. 91 is a pin fixed between the sides 50 of one length of the rail 4 which at its extremities forms a pivot about which the 95 hooks or latches 90 may swing. On the end of the other length of rail is another pin 92 secured in a similar manner between the sides. The ends of this pin 92 form studs or projections adapted to be engaged by the 100 hooked extremities of the latches 90. The horn 88 projects up between the pins 91, 92 and the tread 51 of the rail 4 on the inside rests upon it. An advantage of this construction is that there are no loose parts to 105 be misplaced as the parts are all permanently fixed to the rails.

In the further modification illustrated in Figs. 27 and 28 the rail carrier or horn 88 is provided at the top with two vertical slots 93, 110 and fixed between the sides of the rail are pins 94 which are adapted to drop into the slots 93 in the carrier 88 to secure the rails 4 thereto. The ends of the pins 94 are riveted over on the outside so as to permanently 115 attach them to the rails 4. With this construction the rail 4 may be carried by the pins 94 or the top or tread 51 of the rail may rest upon the top of the horn 88.

The different constructions are designed so 120 that they offer no impediment or obstruction in the path or track of the guide wheels of the bogie at the sides of the rail.

In connection with Fig. 19 I illustrate a 125 flexible joint which may be conveniently employed between the lengths of rail 4 in cases where abrupt changes occur in the inclination of the ground upon which the track is laid. At the end of one length of rail the fish plate 95 is riveted or bolted as at 96 to 130

the inside of the side plates 50. The end of the fish plate 95 is made semi-circular as shown. The side plates 50 of the adjoining length of rail are also made semi-circular and between them projects the semi-circular end of the fish plate 95, a bolt 97, which forms the pivot or hinge, joining these parts. This form of joint allows the rails 4 to be placed at the maximum inclination, either in an upward or downward direction, which the truck is capable of traversing.

In the case of permanent or semi-permanent joints, in place of the construction described in connection with Fig. 19, the fish plates (see Fig. 13) may, as illustrated in Figs. 29 and 30 be lengthened and suitably curved.

In Figs. 39 and 40 I illustrate an arrangement of a two-way switch whereby trucks may pass from either of the two lines on to the single line. It is necessary where two or more tracks converge into one, to provide means for preventing the trucks overrunning the ends of the rail, so that all rail ends shall remain closed and only be opened by the operation of bringing the switch-rail into position. The arrangement illustrated is designed to accomplish this. In the drawings 98, 99, are the two fixed converging rails and 100 is the switch-rail pivoted or hinged from a fixed joint on the single line, and adapted to be brought into position to divert the trucks from either of the converging lines 98, 99, on to the single line, or vice versa. For each of the converging rails 98, 99, I provide a hinged or pivoted arm 101. This latter consists of the bifurcated piece shown pivotally connected to the sleeper 102 carrying the converging rails, by means of the two hinge bolts 103, which are fixed at either side of and below the rail. The swinging arm 101 in proximity to its forward end is constructed with the two vertical projections 104, one at either side of the rail. Beyond the projections 104 the arm 101 is constructed with two parallel projections 105, which form between them a slot or groove 106 adapted to engage the switch-rail 100 and to maintain it in correct position in relation to either of the fixed rails 98, 99. 107 are two rearward extensions of the bifurcated portion of the hinged arm 101, which extensions 107 are shown at their rear extremities joined and formed in one piece with a weight 108. This weight 108 serves to maintain the pivoted arm 101 in the position in which it is shown in dotted lines in Fig. 39. When in this position the vertical projections 104 formed on the arm 101 assume such a position that they are engaged by the guide wheels 16 of the truck and serve as stops therefor, and so prevent the truck leaving the rail. When the switch-rail 100 is in position in the slot 106 formed between the two parallel projections 105 it is thereby locked

in correct position in relation to the fixed rail to divert the trucks on to the single line and at the same time the pivoted arm 101 is placed in such a position that the guide wheels 16 of the trucks do not contact with the stops 104 but pass freely over them. Instead of hinging or pivoting the swinging arms 101 to the sleeper 102 as shown, it will be apparent that they may be hinged to the fixed rails 98, 99, and also that instead of a weight 108 for operating the swinging arm 101, a spring might be employed. The switch-rail 100 is shown supported by a carrier 109 which is adapted to slide on the top of the sleeper 110 to allow the switch-rail 100 to be placed in line with either of the fixed converging rails 98, 99.

To place the switch-rail 100 in line with either of the fixed rails 98, 99, the swinging arm 101 is depressed against the weight 108 and the switch-rail 100 brought into position above the slot 106 formed by the parallel projections 105. The arm 101 is then released and the switch rail 100 engaged by it and locked in position.

In Fig. 41 I illustrate diagrammatically the apparatus arranged for the purpose of conveying ore in stopes from the working faces or points at which the mineral is mined to the stope box 111 from which it is discharged into ordinary trucks 112 for tramping or conveying it along the drives or levels 113 to the shaft for conveyance to the surface. As depicted in this figure the single line track 4 is laid to follow, more or less, the contour of the working face in the stope 114 and at a suitable distance therefrom. After the rock or mineral has been broken by blasting the empty trucks, of which one is represented at 115, are allowed to run down the line to the desired position or positions for loading and they are then allowed to gravitate to the bottom or foot of the stope, at which point the tippler (when one is employed) is located. The tippler is shown arranged on a sheet 116 of metal down which the ore or mineral slides, or is shoveled, to the stope box 111. As previously stated the single line 4 may be continued down into and along the drive or level 113 and the loaded trucks 115 be allowed to gravitate or be propelled to the shaft, and the trucks 112 ordinarily employed for conveying the ore from the stope box 111 to the shaft, be dispensed with. The trucks 115 employed in the stope 114 may be raised and lowered in the stope by means of a steel wire or other suitable rope 117 connected to one or more of the trucks, and trucks traversing different rails in the same stope be arranged to balance one another, the ropes connecting them being run around suitably disposed guide pulleys; that is to say the loaded truck or trucks in running down the stope to the stope box 111 would draw up an empty truck or trucks on

another track. The raising and lowering of the trucks in the stope might alternatively be effected through the medium of the rope 117 by means of a winch or other suitable means located at the top of the stope or in any other suitable position. As the working face is advanced by the displacement of the rock or mineral the line of track 4 is moved with it either by lifting it in sections or 10 "pinching" it along bodily.

When the trucks 115 are run from the stope direct to the shaft the rock or mineral is emptied into the shaft bin and means are preferably provided for raising the empty 15 trucks to the level at the top of the stope. This might conveniently be effected by means of a suitable winch located at or near the shaft.

What I claim as my invention and desire 20 to protect by Letters Patent is:—

1. In apparatus of the nature specified, a vehicle, a bogie upon which said vehicle is mounted, said bogie being adapted to traverse a single rail and having swivel connection with the vehicle so that it may move 25 in both horizontal and vertical directions.

2. In apparatus of the nature specified, a vehicle comprising a body portion and bogies adapted to traverse a single rail, the 30 bogies being constructed so that they can swivel in both a horizontal and vertical plane.

3. In apparatus of the nature specified, in combination, a vehicle body, dish shaped bearing pieces secured to the bottom of the body and forming recesses on the underside, an eyebolt revolvably carried by each bearing piece, a pivot plate revolvably mounted on each eyebolt, a bogie carriage for each 35 bearing piece constructed in its upper portion with holes and a pivot pin for each carriage engaging the holes in the upper portion thereof and engaging holes in the pivot plate and eyebolt.

4. In apparatus of the nature specified, in combination, a vehicle body, dish shaped bearing pieces secured to the bottom of the body and forming recesses on the underside, an eyebolt revolvably carried by each bearing 40 piece and a pivot plate revolvably mounted on each eyebolt and formed with perforated projections on the underside, a bogie carriage for each bearing piece comprising a main frame consisting of two side plates 45 connected by a transverse rib and with two downwardly projecting arms, an axle carried between the side plates at each side of said transverse rib, wheels on each of said axles, a vertical axle carried by each arm, and guide wheels on said axles below the arms.

5. In apparatus of the nature specified, in combination, a vehicle body, dish shaped bearing pieces secured to the bottom of the

body and forming recesses on the underside, 65 an eyebolt revolvably carried by each bearing piece and a pivot plate revolvably mounted on each eyebolt and formed with perforated projections on the underside, a bogie carriage for each bearing piece comprising a main frame consisting of two side plates connected by a transverse rib and with two downwardly 70 projecting arms, an axle carried between the side plates at each side of said transverse rib, wheels on each of said axles, a vertical axle 75 carried by each arm, guide wheels on said axles below the arms, two links fixed on one of the axles of the bogie carriages, a spindle carried by the links, a pair of brake blocks carried by the spindle and means for rotating 80 the spindle to draw the blocks together to apply the brake.

6. In apparatus of the nature specified, a vehicle consisting of a long, narrow, shallow body, divided into a plurality of compartments by transverse division plates, and having dish shaped bearing pieces secured to the bottom of the body and forming recesses on the underside, an eyebolt revolvably carried by each bearing piece, a pivot plate revolvably mounted on each eyebolt, a bogie carriage for each bearing piece constructed in its upper portion with holes, a pivot pin for each carriage engaging the holes in the upper portion thereof and engaging holes in the pivot plate and eyebolt, for providing swivel connection in both a horizontal and vertical direction between the truck body and bogie.

7. In apparatus of the nature specified, 100 the combination with a vehicle comprising a body and bogies adapted to traverse a single rail track, the bogies providing swivel connection with the body in both a horizontal and vertical direction, of guiding 105 strips on the frames of the bogie carriages for the purpose set forth.

8. In apparatus of the nature specified, the combination with a vehicle comprising a body and bogies adapted to traverse a 110 single line track, the bogies providing swivel connection with the body in both a horizontal and vertical direction, each of the side plates of the bogies on the inside having grooves, and guiding strips located and secured in said grooves, said strips being turned outward at their extremities for the 115 purpose set forth.

9. In apparatus of the nature specified, a vehicle consisting of a long, narrow, shallow body, transverse division plates dividing 120 said body into a plurality of compartments, bogie carriages upon which said vehicle body is carried, the bogies being constructed to provide swivel connection in a 125 horizontal and vertical direction between said body and bogies, bridles for connecting the vehicle to the hauling rope and strips

fixed to the ends of the vehicle and serving as buffers therefor and as a protection for the bridles.

10. In apparatus of the nature specified, a vehicle consisting of a long, narrow, shallow body, transverse division plates dividing said body into a plurality of compartments and bogie carriages upon which said vehicle body is carried, the bogies being constructed to provide swivel connection in a horizontal and vertical direction between said body and bogies, a buffer for each end of the body of the vehicle comprising a suitably shaped block of wood fitted to and bedded against the end plates, a protecting and securing strip for said block, and a bridle consisting of a curved bar riveted at its extremities to the ends of the sides of the vehicle body, as and for the purpose set forth.

11. In apparatus of the nature specified, a vehicle consisting of a long, narrow, shallow body, transverse division plates dividing said body into a plurality of compartments, and bogie carriages upon which said vehicle body is carried, the bogies being constructed to provide swivel connection in a horizontal and vertical direction between said body and bogies, a bridle for the vehicle comprising an endless bar running completely around the vehicle and secured thereto by bending the longitudinal upper edges of the vehicle body completely around said bar, and a block located at each end of the vehicle between the end plates and the inside of the ends of the bridle to transmit part of the thrust to the end plates, each of the blocks being of such a shape as to provide a space between them and the ends 40 of the bridle for making connection with the hauling rope.

12. In apparatus of the nature specified, a vehicle consisting of a long, narrow, shallow body, transverse division plates dividing said body into a plurality of compartments and bogie carriages upon which said vehicle body is carried, the bogies being constructed to provide swivel connection in a horizontal and vertical direction between said body and bogies, a bridle for the vehicle comprising an endless bar running completely around the vehicle and secured thereto by bending the longitudinal upper edges of the vehicle body completely around said bar, a block located at each end of the vehicle between the end plates and the inside of the ends of the bridle to transmit part of the thrust to the end plates, each of the blocks being of such a shape as to provide a space between them and the ends 60 of the bridle for making connection with the hauling rope, and a buffer for each end of the body of the vehicle comprising a suitably shaped block of wood fitted to and

bedded against the end plates, and a protecting and securing strip for said blocks.

13. In apparatus of the nature specified, a truck consisting of a long, narrow, shallow body of substantially **W** transverse section, transverse division plates dividing said body into a plurality of compartments, bogie carriages upon which said truck body is supported, the bogies having swivel connection in both horizontal and vertical directions about their point of attachment to the body.

14. In apparatus of the nature specified, a truck consisting of a long, narrow, shallow body, built up of an inverted **V** or substantially **V** girder which constitutes the bottom, transverse division plates, and end plates dividing said body into a plurality of compartments, and sides hinged along their upper edges to the transverse partitions and end plates and adapted to swing outward to discharge the contents of the truck, and bogie carriages on which the truck body is carried, said bogies being constructed to allow of swivel connection in both a horizontal and vertical direction between the body and bogies, as set forth.

15. In apparatus of the nature specified, a truck consisting of a long, narrow, shallow body built up of an inverted **V** or substantially **V** girder which constitutes the bottom, transverse division plates and end plates dividing said body into a plurality of compartments, perforated lugs fixed to the transverse division plates and end plates, a rod for each side of the truck body carried by said perforated lugs, and sides hinged along their upper edges on the aforesaid rods and adapted to swing outward to discharge the contents of the truck, and bogie carriages on which the truck body is carried, said bogies being constructed to allow of swivel connection in both a horizontal and vertical direction between the body and bogies, as set forth.

16. In apparatus of the nature specified, a truck consisting of a long, narrow, shallow body, built up of an inverted **V** or substantially **V** girder which constitutes the bottom, transverse division plates and end plates dividing said body into a plurality of compartments, and sides hinged along their upper edges to the transverse partitions and end plates and adapted to swing outward to discharge the contents of the truck, means for automatically releasing the sides to discharge the contents of the truck, said means comprising brackets riveted to the hinged side, a bar slidably supported in said brackets, said bar being provided with projections, pieces riveted to the division plates and end plates, which pieces project through holes in the hinged side, said pieces being formed with slots engaging the projections on the bar, a depending arm pivoted to the side and a

roller fixed to the bar adapted to be engaged by said arm, a fixed stop adapted to engage the aforesaid arm to move the latter into engagement with the roller and to slide the 5 bar longitudinally of the side to cause the projections to disengage the slots in the aforesaid pieces, and bogie carriages on which the truck body is carried, said bogies being constructed to allow of swivel connection in both 10 a horizontal and a vertical direction between the body and bogies, as set forth.

17. In apparatus of the nature specified, a single line track of rails, supports for the rails arranged in proximity to their extremities only, and serving for supporting the contiguous ends of successive lengths of rail, means for connecting the lengths of rail through the medium of said supports, said means permitting the rails to adjust themselves to the gradient of the surface on which they are laid and also if required to a lateral change of direction, as set forth.

18. In apparatus of the nature specified, a single line track consisting of rails comprising 25 a sheet of metal bent to form two parallel and vertical sides and a tread joining the sides, and means consisting of tubular or other distance pieces located between the sides, and rivets passing through said tubular distance pieces and riveted to the sides for maintaining the latter parallel, as set forth.

19. In apparatus of the nature specified, a single line track consisting of rails comprising 35 a sheet of metal bent to form two parallel and vertical sides and a tread joining the sides, and in which one side of the rail is bent inward at the bottom to form an internal flange and the other bent inward at the bottom to 40 form an external and overlapping flange, and rivets connecting said flanges as set forth.

20. In apparatus of the nature specified, a single line track consisting of rails comprising 45 a sheet of metal bent to form two parallel and vertical sides and a tread joining the sides, and in which the parts which form the sides are provided with external projecting ridges, as and for the purpose set forth.

21. In apparatus of the nature specified, in 50 combination, a truck body, bogies adapted to traverse a single line track, the bogies being constructed so that they can swivel about the body in both a horizontal and vertical plane, the bogies being provided with guide 55 wheels, a single line track consisting of rails

each comprising a sheet of metal bent to form two parallel and vertical sides and in which the parts which form the sides are provided with external projecting ridges forming guide and check strips for the wheels, as 60 set forth.

22. In apparatus of the nature specified, in combination, a single line track consisting of rails, each rail comprising a metal plate bent to form two parallel and vertical sides and a tread joining the sides at the top, the sides being also connected at the bottom, a rail carrier consisting of a sleeper, and a horn fixed thereto, which latter is adapted to project between the parallel sides of the rail so 65 that the lower edges of the latter rest upon the top of the sleeper, as and for the purpose set forth.

23. In apparatus of the nature specified, a single line track consisting of rails comprising 75 a sheet of metal bent to form two parallel and vertical sides and a tread joining the sides, and means for flexibly connecting the ends of successive lengths of rail when abrupt changes occur in the inclination of the ground 80 upon which the track is laid, said flexible means consisting of a fish plate fixed between the side plates at the end of one length of rail the outer end of said fish plate being semi-circular, and the side plates at the end 85 of the adjoining length of rail being semi-circular to receive the semi-circular end of the fish plate, and a bolt which passes through the semi-circular ends of the side plates and semi-circular end of the fish plate and forms 90 a hinge, as and for the purpose set forth.

24. In apparatus of the nature specified, a single line track consisting of rails comprising two vertical and parallel side plates and a tread of means for making permanent or 95 semi-permanent joints between the contiguous extremities of successive lengths of rail, comprising a suitably curved fish plate, the extremities of which project between the side plates of the rails, the extremities of the fish 100 plates and side plates being formed with coincident holes for connecting them, as and for the purpose set forth.

In witness whereof I have hereunto set my hand in the presence of two subscribing witnesses this 23rd day of January, 1907.

ALFRED EDWIN DAVIS.
